UNITED STATES PATENT OFFICE.

SAMUEL H. GREGG, OF CRAWFORDSVILLE, INDIANA.

MANUFACTURE OF BARBED STRIPS FOR FENCES.

SPECIFICATION forming part of Letters Patent No. 258,412, dated May 23, 1882.

Application filed February 6, 1882. (No model.)

To all whom it may concern:

Be it known that I, SAMUEL H. GREGG, of Crawfordsville, in the county of Montgomery and State of Indiana, have invented a new 5 and useful Improvement in the Manufacture of Barbed Metallic Corrugated Strips for Fencing; and I do hereby declare that the following is a full, clear, and exact description of the same, reference being had to the accompanying drawings, forming part of this specification, in which—

Figure 1 is a side elevation of a pair of rolls having oval grooves. Fig. 2 is a like view, showing recesses for forming the barbs. Fig. 15 3 is a cross-section of the oval rod, showing the barbs. Fig. 4 is a side elevation of a pair of rolls having square grooves. Fig. 5 is a transverse section of a pair of corrugated rolls, and Fig. 6 shows a plan and side view of the 20 finished barbed and corrugated strip.

My invention relates to improvements in the manufacture of barbed metallic corrugated strips for fencing; and it consists, first, in the peculiar construction of the rolls, whereby 25 each strip, with its barbs, is formed in one piece. My invention further consists in the general process, whereby a round bar of metal is converted into a barbed metallic strip of peculiar construction by passing it through a 30 series of peculiarly-constructed rolls; and my invention finally consists of the barbed metallic corrugated fencing-strip, produced as hereinafter more fully set forth.

In the accompanying drawings I first roll 35 the metal from which the fencing-strip is to be formed between fluted rolls until it is reduced to the proper size and of round form. I then pass the round bar or rod through a pair of rolls, *a a*, having oval grooves *a' a'*, 40 rendering the bar oval in cross-section. The bar or rod is then passed through another pair of rolls, *b b*, provided with oval grooves *c c*, which have angular notches or recesses *d d* cut in their sides and lying directly opposite 45 each other. The angular recesses *d* are cut in a V shape and taper to a point, as shown in the drawings. In passing the steel or other metal through the rolls *b b* the metal is forced into the angular recesses *d*, thus forming spurs 50 or barbs *e* on the oval rods at proper intervals apart, which lie directly opposite each other and on opposite sides of the oval bar or rod. The oval rod, provided with spurs *e*, is then passed between the rolls *h h*, provided with

flat square grooves *i i*, whereby the oval rod 55 is flattened and reduced to the desired width and thickness. The strip and barbs are then trimmed and passed between a pair of rolls, *m m*, fluted longitudinally, or provided with longitudinal grooves *n n*, which crimp or corrugate the strip and its barbs to strengthen them and allow for contraction and expansion from cold and heat. By this process it will be seen that a metallic fencing-strip, *A*, provided with opposite barbs, *e*, in the plane of 65 the strip, and projecting upwardly and downwardly from its upper and lower edges, and corrugated transversely, is cheaply and rapidly produced, forming a fencing-strip in which the barbs form an integral part of the strip, 70 and are not liable to slip thereon, and the strip is corrugated transversely to strengthen it and allow for expansion and contraction from heat and cold.

What I claim as my invention is—

1. The combination of the rolls *b b*, provided with oval grooves *c c*, having angular recesses *d d* cut in their sides, and lying directly opposite each other, substantially as described, and for the purpose set forth.

2. The process herein described of manufacturing metallic corrugated barbed fencing-strips, consisting in first passing a round bar or rod through a pair of rolls having oval grooves formed therein, then passing said bar 85 or rod through a second pair of rolls provided with oval grooves having angular recesses cut in their sides, and lying directly opposite each other, then passing the oval bar provided with spurs between rolls provided with flat square 90 grooves to flatten and reduce the thickness of the rod, then trimming the strip and its barbs, and finally passing it through a pair of rolls grooved longitudinally, whereby the strip and its barbs are crimped or corrugated transversely, as set forth.

3. As an improved article of manufacture, the metallic fencing-strip *A*, corrugated transversely, and provided with opposite barbs in the plane of the strip and integral therewith, 100 and projecting upwardly and downwardly from its upper and lower edges, as and for the purposes specified.

SAMUEL H. GREGG.
